E. F. HATHAWAY

SUSPENSION MEANS FOR TUBE FRAMES

Filed May 24, 1922

UNITED STATES PATENT OFFICE.

EDGAR F. HATHAWAY, OF WELLESLEY, MASSACHUSETTS, ASSIGNOR TO SHAWMUT ENGINEERING COMPANY, OF BOSTON, MASSACHUSETTS, A CORPORATION OF MASSACHUSETTS.

SUSPENSION MEANS FOR TUBE FRAMES.

Application filed May 24, 1922. Serial No. 563,243

To all whom it may concern:

Be it known that I, EDGAR F. HATHAWAY, a citizen of the United States, and resident of Wellesley, in the county of Norfolk and

6 State of Massachusetts, have invented certain new and useful Improvements in Suspension Means for Tube Frames, of which the following is a specification.

This invention relates to suspension means 10 for tube frames used in the weaving of pile fabrics such as Axminster carpets and the like and is intended to provide a secure, reliable and simple construction by which tube frames may be securely held in their carrier chains while permitting the automatic release and return of the tube frame to its supporting carrier.

It has formerly been the commercial practice to employ for the suspension of a tube 20 frame from its carrier chains a pair of co-acting arms or connecting members at each end the other being provided with a hook at its end and being made of spring metal to yield under the pressure of the tube frame 25 transfer clutches in order to permit release from the chain while holding the tube frame normally suspended from the feed chain. One of the weak points in this old construction is that an accidental blow or contact 30 against the end of the spring arm may release the hook and allow the tube frame to drop into the loom thereby causing much damage and trouble.

The present invention overcomes such difficulties by providing positively locked but automatically releasable suspension means by which the tube frame is securely locked to its carrier chains, while the parts are so arranged as to be readily released by the 40 transfer clutches which act to transfer the tube frame from its carrier chain to position for use in the weaving operation when it is required. This and other features of the invention will be explained in the following specification and will be defined in the claims hereto annexed. The specific features of construction shown in the modified or alternative form of construction 45 illustrated in Figures 7, 8 and 9 are not 50 specifically claimed herein but are made the subject matter of a divisional application filed by me on the 4th day of May 1923, now Patent No. 1,469,185, granted Sept. 25, 1923.

In the accompanying drawings I have shown different forms illustrating the practical application of the principles of this invention, in which:

Figure 1 is a front elevation showing the end of a tube frame with suspension members embodying the present invention in locked position on the chain which is shown in dotted lines, the principal parts being shown in a vertical cross section.

Figure 2 is a plan view of the construction shown in Figure 1.

Figure 3 is an end elevation of the suspension means viewed from the inside.

Figure 4 is a view similar to Figure 1 but showing the hook arm of the suspension means open to release the hook member from locked position either for transferring the tube frame from the sprocket chain or for transferring it to the sprocket chain after the tube frame has been in use.

Figure 5 is a view similar to Figure 4 but showing the hook arm in an intermediate position.

Figure 6 shows a slightly modified form in which a tension spring is used to insure closing of the hook arm or jaw.

Figures 7 and 8 are front elevations in cross section of modified forms shown in two different positions of action.

Figure 9 is an end elevation thereof.

As will be understood by those skilled in the art of weaving pile fabrics, such as carpets, the pile forming tuft elements of yarn comprising yarn of different shades or colors are wound on spools of tube frame in a predetermined order or arrangement in correspondence with the desired pattern and have their free ends projecting slightly from the delivery ends of hollow needles or tuft tubes which guide them into position between the warp threads of the fabric. A large number of these tuft tubes are arranged in sequence in the links of parallel sprocket chains or carriers from which they are suspended by means of suspension arms or jaws arranged in co-operating pairs at each end of the tube frame. These suspension members usually comprise a link-penetrating arm and a co-acting arm or jaw formed at its upper end with a retaining hook and made of spring metal so as to yield to release the hook from retaining engagement with the chain. This release is effected

by means of a suitably arranged pair of transfer clutches which are positioned to arise at opposite ends of the tube frame to engage the overhead or aligned ends of the tube frame, release the hooks, carry the tube frame into position for use and thereafter return it to interlocked engagement with the carrier chains. Now as any accidental blow or pressure against the exposed spring tongue or hook arm of the suspension means will operate to release the hook and allow the tube frame to fall out of the chain, the above described arrangement is not secure and fool-proof. This difficulty is overcome by providing a positive latch for fastening the hook arm in closed or locking position, the latch being so arranged as to be automatically operated by the transfer clutch either preliminary to releasing the tube frame from the carrier chains or when reinserting the tube frame in the carrier chains.

Any suitable form of tube frame may be employed in the practice of this invention. In this case the tube frame is shown as including a hollow or tubular carrier bar *a* which forms the backbone of the frame and to each end of which is secured a suspension bracket or member *l* which is rigidly secured to the carrier bar *a* in any suitable manner. In the present instance this suspension bracket or member *l* is made in one piece out of properly cut and bent sheet metal and comprises the upright or vertical arm provided with inwardly turned arms 2 and 3 properly spaced and bent to snugly fit inside the open end of the tubular carrier bar *a*. These inturned flange portions 2 and 3 may be provided with tapped apertures for the reception of fastening screws, and for additional guiding means the end bracket *l* has inwardly turned ears or lugs 4 to engage the side walls of the tube 2. At its upper end the bracket *l* is bent at right angles to form a horizontal portion 5 which is again bent vertically to form a pointed tongue 6. At an intermediate portion of the middle this plate is bent up vertically inside of the vertical plane of the bracket to form an ear 7 which is perforated to receive the journal of a yarn spool *d*, shown in dotted lines in Figure 1.

The carrier chain is of the usual sprocket chain type illustrated in dotted lines at *c* in Figure 1 and other figures, the upwardly projecting tapered or pointed tongue at 6 having sufficient length to penetrate between the sides of the chain link and project upward some distance above the top of the chain to coat and form a stop for the hook arm of the suspension couple. The horizontal portion 5 of the rigid bracket is provided with downwardly projecting wings or flanges 8 which support a horizontal fulcrum pin 11 on which is fulcrumed the fas-

tening jaw or hook member 12, which is provided at its upper end with a bent portion to form a hook 12^a, to overlap the upper end of the chain for locking purposes and which is formed at its bottom with parallel arms 12^b, extending inwardly to form supporting arms pivotally mounted on the fulcrum pin 11. At their rear ends these horizontal extensions 12^b, are provided with downward extensions having bevelled edges 12^c, to be engaged by the transfer clutch as will be hereinafter explained.

Between the two parallel arms 12^b is pivoted on a cross-connecting pin 12^d a latch comprising parallel side portions 13, and a cross-connecting portion 14 projecting inwardly beyond the side members to form a ledge or shoulder 13^a to engage the edge of a recess 9 formed in the horizontal extension 5, of the suspension arm 1. A torsion spring 15, around the fulcrum axis 12^d of the latch 13, acts to normally throw the latch in a contraclockwise direction as shown in Figures 1 and 4.

The movable arm 12, and the latch 13, 14, are so related that when the hook 12^a is in closed position, that is, in contact with the link-penetrating tongue 6, the shoulder 13^a of the latch is engaged with the edge of the aperture in the horizontal member 5. Now as the arm 12 must swing in a clockwise direction to release the suspension means from the carrier chain, it will be seen that the latch at 13^a prevents any such rotative movement and therefore positively holds the movable arm of the suspension means in locked position so that no pull or pressure outwardly against the hook 12^a will act to release or detach the movable or locking arm from locked position. It will also be noticed that the arm 12 is provided at its outer lower end with a bent lip 12^e. The operation of the device is as follows.

The transfer clutch which is of the usual construction, and therefore as shown in dotted lines at *b*, has two movements, a vertical movement to position shown in Figure 1, and an inward horizontal movement to position shown in Figure 4. It will be understood that this inward horizontal movement, by reason of the sloping cam or hook at the bottom portion of the clutch member *b*, serves to lift the tube frame slightly to relieve the supporting strain on the hook 12^a of the movable jaw 12, to permit the easy release of said hook from chain-engaging position. In its position in Figure 1, the transfer clutch is ready to act, but has not yet acted upon the suspension means. Its first inward movement engages and releases the latch at 13^a by causing a clockwise rotation of said latch against the tension of the torsion spring 15. The further inward movement of the clutch, by reason of the engagement of the cam at its lower end in the

UNITED STATES PATENT OFFICE.

EDGAR F. HATHAWAY, OF WELLESLEY, MASSACHUSETTS, ASSIGNOR TO SHAWMUT ENGINEERING COMPANY, OF BOSTON, MASSACHUSETTS, A CORPORATION OF MASSACHUSETTS.

SUSPENSION MEANS FOR TUBE FRAMES.

Application filed May 24, 1922. Serial No. 563,243

To all whom it may concern:

Be it known that I, EDGAR F. HATHAWAY, a citizen of the United States, and resident of Wellesley, in the county of Norfolk and

6 State of Massachusetts, have invented certain new and useful Improvements in Suspension Means for Tube Frames, of which the following is a specification.

This invention relates to suspension means 10 for tube frames used in the weaving of pile fabrics such as Axminster carpets and the like and is intended to provide a secure, reliable and simple construction by which tube frames may be securely held in their carrier chains while permitting the automatic release and return of the tube frame to its supporting carrier.

It has formerly been the commercial practice to employ for the suspension of a tube 20 frame from its carrier chains a pair of co-acting arms or connecting members at each end the other being provided with a hook at its end and being made of spring metal to yield under the pressure of the tube frame 25 transfer clutches in order to permit release from the chain while holding the tube frame normally suspended from the feed chain. One of the weak points in this old construction is that an accidental blow or contact 30 against the end of the spring arm may release the hook and allow the tube frame to drop into the loom thereby causing much damage and trouble.

The present invention overcomes such difficulties by providing positively locked but automatically releasable suspension means by which the tube frame is securely locked to its carrier chains, while the parts are so arranged as to be readily released by the 40 transfer clutches which act to transfer the tube frame from its carrier chain to position for use in the weaving operation when it is required. This and other features of the invention will be explained in the following specification and will be defined in the claims hereto annexed. The specific features of construction shown in the modified or alternative form of construction 45 illustrated in Figures 7, 8 and 9 are not 50 specifically claimed herein but are made the subject matter of a divisional application filed by me on the 4th day of May 1923, now Patent No. 1,469,185, granted Sept. 25, 1923.

In the accompanying drawings I have shown different forms illustrating the practical application of the principles of this invention, in which:

Figure 1 is a front elevation showing the end of a tube frame with suspension members embodying the present invention in locked position on the chain which is shown in dotted lines, the principal parts being shown in a vertical cross section.

Figure 2 is a plan view of the construction shown in Figure 1.

Figure 3 is an end elevation of the suspension means viewed from the inside.

Figure 4 is a view similar to Figure 1 but showing the hook arm of the suspension means open to release the hook member from locked position either for transferring the tube frame from the sprocket chain or for transferring it to the sprocket chain after the tube frame has been in use.

Figure 5 is a view similar to Figure 4 but showing the hook arm in an intermediate position.

Figure 6 shows a slightly modified form in which a tension spring is used to insure closing of the hook arm or jaw.

Figures 7 and 8 are front elevations in cross section of modified forms shown in two different positions of action.

Figure 9 is an end elevation thereof.

As will be understood by those skilled in the art of weaving pile fabrics, such as carpets, the pile forming tuft elements of yarn comprising yarn of different shades or colors are wound on spools of tube frame in a predetermined order or arrangement in correspondence with the desired pattern and have their free ends projecting slightly from the delivery ends of hollow needles or tuft tubes which guide them into position between the warp threads of the fabric. A large number of these tuft tubes are arranged in sequence in the links of parallel sprocket chains or carriers from which they are suspended by means of suspension arms or jaws arranged in co-operating pairs at each end of the tube frame. These suspension members usually comprise a link-penetrating arm and a co-acting arm or jaw formed at its upper end with a retaining hook and made of spring metal so as to yield to release the hook from retaining engagement with the chain. This release is effected

in operative closed relation, said locking means being automatically releasable to permit the opening of said arms to disengage them from the carrier, substantially as described.

2. Suspension means for tube frames embracing in combination a pair of coacting suspension arms for supporting each end of a tube frame, comprising a link penetrating arm and a movable arm provided with an offset hook portion disposed to overlap the carrier chain when in closed position, and a locking detent arranged to hold the hook arm against opening movement when pressure is exerted against the hook arm, said detent being disposed to be engaged and released by the movement of the transfer clutch, substantially as described.

3. In a tube frame the combination of a carrier bar, an upwardly extending link penetrating arm rigidly secured thereto, a hook arm pivotally connected with the aforesaid link penetrating arm, and a latch arranged to automatically lock the pivotal arm when the latter is in closed operative position, said latch being mounted to be automatically released from locking position during the initial part of the hook-releasing movement of the transfer clutch of the loom, substantially as described.

4. Suspension means for a tube frame embracing in combination a link-penetrating arm adapted to be secured to the tube frame, a coacting hook arm connected therewith to permit its hook end to move toward and away from the link-penetrating arm to permit operative engagement with and release from a tube frame carrier chain, the hook arm being mounted to be moved by a transfer clutch out of closed operative position to release the tube frame from the carrier and to be moved into closed operative position by the reverse movement of the clutch, and automatically releasable means for locking the hook arm in closed position, substantially as described.

5. Suspension means for a tube frame embracing in combination two coacting suspension arms flexibly connected together for operative engagement with and release from an overhead carrier, said members being normally held in a predetermined relationship under spring tension, the movable member being arranged to be shifted against said spring tension by the movement of a transfer clutch, and means releasable by the movement of the transfer clutch for locking the movable member in closed relation, substantially as described.

6. Suspension means for a tube frame embracing in combination a pair of flexibly connected coacting suspension arms each provided with an offset portion disposed to project respectively above and below an overhead carrier when in operative relation

for suspension engagement therewith, and means for locking them in such operative relation, said locking means being automatically releasable when the transfer clutch of the loom moves to position to release said suspension means in order to transfer the tube frame for use in the weaving operation, substantially as described.

7. Suspension means for a tube frame embracing in combination two coacting suspension members arranged when closed together to form operative suspension engagement with an overhead carrier, and a spring latch mounted on one of said members in position to releasably lock them in closed relation, said latch being arranged to be engaged and released against its spring tension by the transfer clutch of the loom as the latter moves to position to open the suspension members and to automatically move to locking position when the suspension members are closed, substantially as described.

8. Suspension means for a tube frame embracing in its construction two coacting suspension members flexibly connected together to permit them to close and to open for operative engagement with or release from a tube frame carrier, the movable member being constructed with one portion arranged to be engaged by the transfer clutch of the loom for movement into open position and with another portion arranged to be engaged by the reverse movement of the clutch for movement into closed position, substantially as described.

9. Suspension means for a tube frame embracing in combination flexibly connected coacting suspension members arranged to have suspension engagement with a suitable carrier when in closed relation, and a locking detent mounted in one of said members in position to form locking engagement with the edge of an aperture in the other member when the members are closed and to pass into said aperture when the members are opened, said detent tending normally to move to locking position and being released therefrom by the pressure of the transfer clutch, substantially as described.

10. In a tube frame, a hollow tube, a spool bearing bracket formed of a single piece of sheet metal and having integral side and bottom supporting portions adapted to project within said tube, and means to secure said bracket in position.

11. In a tube frame, a hollow tube, a spool bearing bracket formed of a single piece of sheet metal, said bracket having a bearing portion and having side and bottom supporting portions extending within said tube by which said bracket may be secured in operative position in the tube, and means to secure said parts together.

12. In a loom, a pattern chain, a sup-

porting tube, a spool bearing bracket comprising a chain engaging portion, a bearing portion, and side and bottom portions by which said bracket may be secured in operative position in the tube, and means to secure said bracket in position, all parts of said bracket being formed of a single piece of sheet metal.

13. Suspension means for a tuft tube frame embracing in combination with a carrier-chain, a tube frame suspending member adapted to afford a releasable suspending connection between the tube frame and the carrier-chain, a spring latch arranged, when actuated by its spring, to normally lock the suspension member against withdrawal from such suspending connection, the latch being positioned to be retracted by the transfer mechanism to per-

mit release of said suspending connection, substantially as described.

14. Means for suspending a tuft tube frame from its carrier chains, embracing in combination with a carrier-chain, a suspension member adapted to afford a releasable suspending connection between the tube frame and the carrier-chain to permit transfer of the tube frame to the loom, co-acting means for positively locking said suspension member against withdrawal from such connecting relation, said locking means being itself releasable by automatic means preliminary to transfer of the tube frame to the loom.

In witness whereof, I have subscribed the above specification.

EDGAR F. HATHAWAY.
